(57) **CLAIM**

The ornamental design for a tool for placement of markings, as shown and described.

DESCRIPTION

FIG. 1 is a perspective view of a tool for placement of markings showing my new design;

FIG. 2 is a front view of the tool for placement of markings;

FIG. 3 is a top view of the tool for placement of markings;

FIG. 4 is a left side view of the tool for placement of markings;

FIG. 5 is a right side view of the tool for placement of markings;

FIG. 6 is a rear view of the tool for placement of markings; and,

FIG. 7 is a bottom view of the tool for placement of markings.

The broken lines define the bounds of the claimed design and form no part thereof.
